UNITED STATES PATENT OFFICE.

THOMAS H. SYMINGTON, OF BALTIMORE, MARYLAND.

JOURNAL-BOX LID.

SPECIFICATION forming part of Letters Patent No. 739,516, dated September 22, 1903.

Application filed March 24, 1903. Serial No. 149,368. (No model.)

To all whom it may concern:

Be it known that I, THOMAS H. SYMINGTON, a citizen of the United States of America, and a resident of 1169 Calvert Building, Baltimore, Maryland, have invented certain new and useful Improvements in Journal-Box Lids, of which the following is a specification.

My invention relates to certain improvements in journal-boxes, particularly to the construction of the lid therefor and means for holding the lid open and closed.

The particular object of my invention is to provide a lid of the hinged type which will rest firmly on its seat all the way round and which will be held tightly to the seat, whereby by the lid will form a dust-tight cover for the box.

With these objects in view the invention relates to certain constructions and combinations of parts, the preferred form of which will be first particularly described and the invention pointed out in the claims.

Referring to the drawings, wherein like parts are represented by the same reference-numeral wherever they occur, Figure 1 is a side elevation of a journal-box, partly in section, showing my lid applied thereto. Fig. 2 is a transverse section taken on line 2-2 of Fig. 1, showing the spring and pivot-bolt in elevation. Fig. 3 is a detailed sectional view showing one of the ears by which the lid is pivoted to the box and the way in which it is pivoted. Fig. 4 is a view similar to Fig. 3, showing the lid in its open position. Fig. 5 is a detail view of the arm which holds the lid to its seat. Fig. 6 is a detached detail view of the ears of the lid. Fig. 7 is a detached detail view of the springs which actuate the arm for pressing the lid to its seat. Fig. 8 is a view similar to Fig. 1, showing the modified form of the means for holding the lid to its seat. Fig. 9 is a detailed view of the spring used in the form of construction shown in Fig. 8.

1 designates a journal-box of any desired type provided with the usual opening in its front. The opening has a seat 2 round the same, on which the lid 3 is adapted to rest.

4, 4 are a pair of ears suitably spaced apart, preferably formed integral with the box. I 50 have shown these ears as extending up from the top of the box; but it is to be understood that these ears can be placed at the side or

bottom of the box without departing from my invention.

The lid 3 is provided with a pair of ears 55 5, preferably and as shown at the upper corners of the lid, and 6 is an elongated opening passing through the ears, by which the lid is pivoted to the box. The purpose of having this opening elongated will hereinafter 60 be described.

7 is a bolt passing through the pair of ears 4 and 5 and on which the lid swings. As shown, this bolt is provided at one end with a head 8 and at the other end with a slot 65 through which the cotter-pin 9 is passed to hold the bolt in position. It will be understood, however, that any other form of securing means might be used to hold the bolt in place.

70 Referring now particularly to Figs. 1 to 7, inclusive, 10 designates a lever which is provided at one end with a head 11, the head being cored out at 12, and in the side of this cored-out portion is located a longitudinal 75 slot 13. The ends of the head on the rear side thereof are cut away at 14 for a purpose which will be hereinafter described. 15 15 are a pair of springs having their free ends 16 17 in line with each other, as best shown 80 in Figs. 1 and 7. These springs are oppositely coiled, as there shown, so that when they are brought together, as shown in Figs. 2 and 7, their inner ends 16 will be adjacent to each other and extending in the same direction, while their other ends 17 17 will be on the outer ends of the springs and extending in the same direction. The inside diameter of the coils of these springs is such that they will fit the bolt 7, and the outside 90 diameter of the coils is such that they will freely pass into the opening 12 of the head 11 and form what is practically a bushing upon which the head may turn. In assembling the parts the springs are placed with 95 their inner ends 16 16 in the slot 13, and the outer ends 17 17 will then extend through the cut-away portions 14 14 of the head.

18 is a projection preferably integral with the box and so positioned on the box that it 100 will stand when the parts are assembled immediately behind and partly encircling the head 11, as best shown in Fig. 1. This projection 18 is provided with suitable openings

24, into which the outer ends 17 17 of the springs may be inserted.

19 19 are wedge-shaped lugs on the rear side of the ears 5 5 of the lid.

5 20 designates a cut-away groove in the upper corners of the box just below the face 21 on the top of the box. This construction is best shown in Figs. 3 and 4.

22 is a lug provided near the center of the 10 lid 3 within the area of the seat under which the outer free end of the arm 10 engages.

When the device is assembled in the manner shown and described and the parts are in a position shown in Figs. 1 and 3, it will be 15 seen that the tension of the springs 15, acting through the arm 10 on the lid, will, because of the elongated opening, tend to move the lid toward its seat, and consequently the rear end of the elongated slot will be moved 20 away from the pivot-bolt 7, so that the parts will stand in substantially the position shown in Fig. 3. When now the lid is opened, the springs 15 will force the rear end of the slot 6 away from the bolt 7 until the projection 19 25 comes in contact with the surface 21 and moves thereon, being held against the surface 21 by the springs 15 until the projections 19 are forced down into the cut-away portion 20, when the parts will be in the position 30 shown in Fig. 4 and the lid will be held open against the tension of the springs 15. When it is desired to close the lid, it is only necessary to press downward on the free end of the lid hard enough to cause a camming action 35 between the side of the projections 19 and the side of the cut-away portion 20, lifting the projections 19 out of the cut-away portions 20, and as soon as the projections 19 are clear of the cut-away portions 20 the 40 springs 15 will force the lid down onto its seat. The elongated slots 6 are substantially vertical to the seat, and, besides allowing the motion above described for the purpose of bringing into action means for holding the 45 lid open, perform two other very important functions, which are: they permit the lid to move freely toward and away from its seat without interference by the pivot-bolt 7; hence when pressure is exerted on the center 50 of the lid by the arm 9 then pressure will be equally distributed on the seat all around the seat, while at the same time the slot, being substantially horizontal, prevents vertical motion of the lid on the seat.

55 Referring to the modifications shown in Figs. 8 and 9, it will be noticed that I have dispensed with lever 10 and substituted therefor a spring-arm 23, which is a part of the spring 24. The rest of the construction shown 60 in this modification is the same as that heretofore described. The spring 24 surrounds the bolt 7 in the manner previously described, and its free ends 25 pass through openings in the projection 18 on the box. The outer end 65 of the spring-arm 23 is engaged under lug 22 on the lid in the same manner and for

the same purpose that the lever 20 engages this lug.

While I have described what I believe to be the preferred form of my invention, I desire 70 to have it understood that many modifications and mechanical changes might be made therein without departing from the spirit of my invention.

Having thus described my invention, what 75 I claim as new, and desire to secure by Letters Patent, is—

1. The combination with a journal-box having an opening provided with a seat, of a lid, provided with projections, hinged to the box, 80 and a spring adapted to exert its pressure on the lid within the area of the seat to hold the lid to its seat, the projections being adapted to coöperate with the box to hold the lid open against the tension of the spring. 85

2. The combination with a journal-box having an opening provided with a seat, of a lid provided with elongated pivotal openings, a bolt carried by the box and passing through the elongated openings, a spring adapted to 90 exert its pressure on the lid within the area of the seat and means carried by the lid adapted to coöperate with the box to hold the lid open against the tension of the spring. 95

3. The combination with a journal-box having an opening provided with a seat, of a lid having a lug provided with an elongated opening, a projection on the lug, a bolt carried by the box and passing through the elongated opening whereby the lid is hinged to 100 the box, there being a depression on the box, and a spring carried by the box and adapted to exert its pressure on the lid within the area of the seat, the projection carried by the lug being adapted to coöperate with the depression on the box to hold the lid open against the pressure of the spring. 105

4. The combination with a journal-box having an opening provided with a seat, of a lid provided with a pair of lugs each having an 110 elongated opening, a projection on each lug, a bolt carried by the box and passing through the elongated openings whereby the lid is hinged to the box, there being depressions on the box, and a spring carried by the box and 115 adapted to exert its pressure on the lid within the area of the seat, the projections on the lugs being adapted to coöperate with the depressions on the box to hold the lid open against the pressure of the spring. 120

5. The combination with a journal-box having an opening provided with a seat, of a lid hinged to the box, a bolt by which the lid is hinged, a lever mounted on the bolt, the free end of which bears on the lid within the area 125 of its seat, a coil-spring, one end of which is secured to the box and the other end to the lever, the coils of the spring forming a bushing between the lever and the bolt.

6. The combination with a journal-box having an opening provided with a seat, of a lid provided with elongated openings, a bolt car-

ried by the box and passing through the elongated openings whereby the lid is hinged to the box, a lever on the bolt, the free end of the lever bearing on the lid within the area 5 of its seat, a coil-spring, one end of which is secured to the box and the other end to the lever, the coil of the spring forming a bushing between the lever and the bolt, and means carried by the lid and adapted to coöperate

with a part of the box to hold the lid open to against the tension of the spring.

Signed by me at Baltimore, Maryland, this 17th day of March, 1903.

THOMAS H. SYMINGTON.
